G. R. Moore,

Oscillating Meter,

N° 82,737.

Patented Oct. 6, 1868.

United States Patent Office.

GEORGE R. MOORE, OF LYONS, IOWA.

Letters Patent No. 82,737, dated October 6, 1868.

IMPROVEMENT IN WATER-METERS.

The Schedule referred to in these Letters Patent and making part of the same.

TO ALL WHOM IT MAY CONCERN:

Be it known that I, GEORGE R. MOORE, of the city of Lyons, in the county of Clinton, and State of Iowa, have invented a new and useful Machine for Measuring Running Water—a Water-Meter; and I do hereby declare that the following is a full, clear, and exact description of the construction and operation of the same, reference being had to the annexed drawings, making a part of this specification.

Figure 1 is an end view, with one head removed, and thus shows endwise all the internal machinery of the meter.

Figure 2 is an end view when the head is in its place.

Figure 3 is a vertical view of the internal machinery.

Figure 4 is a side view of a kind of catch or pawl, by which the ratchet-wheel is turned.

Figure 5 is given to show an additional plan for moving the valve, and

Figure 6 an additional plan for moving the ratchet-wheel.

Figs. 5 and 6 are given simply as optionals.

Observe, now, that the space in the cylinder is divided into three apartments by solid and stationary divisions, as follows:

Fig. 3, which is a vertical view of most of the internal machinery of the meter, consists, first, of a plate, A, extending the whole length of the cylinder, and width also, where it is placed, which is about half way from the centre point of the diameter to the circumference below; thus the cylinder is divided into two apartments; second, there is a cross-piece below the plate A, the location of which is indicated by the dotted lines b b, and which perfectly subdivides all that portion of the cylinder which is covered by the plate A.

Now, keeping in mind these three apartments of the meter, it will be seen that both the inlet c and the discharge-pipe, shown by dotted lines, d, are located in the heads of the cylinder alike, each of them below the plate A, so that no water can pass from the inlet to the outlet-pipe, without first passing up through the plate A, then down again through it on the other side of b b. Therefore, the plate A has four openings, at least, (it may have many more,) o o o o. These are water-ways, and two are upon each side of the cross-section b b, and they are alternately opened and closed by the valve B, which closes but two at a time, one on either side of b b, so that there is always one place open for the water to pass into the meter through A, and one for it to pass out.

The valve B is operated by the forcing-plate C, which turns upon journals at the centre of the cylinder, and extends the entire length of it, and sweeps about half the circle.

The valve B and the forcing-plate C have between them the two operating-levers a a, and the operation of moving the valves, and of measuring the water, is as follows:

First, let C be resting upon a at the right-hand side. The valve B will then be turned, so as to open the water-way towards the inlet-pipe, and on that side of the cross-section b b.

Now, there is a solid partition, e, extending the whole length of the cylinder, and from the journals of C down to the plate A, so that the water has no way of escape but to push C over on to the opposite a, where it instantly changes the valve and opens the water-way under C towards the inlet-pipe, and closes the other. This alternating motion continues steadily; C passes over first to one a, and, then to the other, and regularly alternates the valve B.

But in case the water is drawn from the meter so slowly as to bring C around upon a, on either side, so gently as not fully to change the valve, then the springs d d, yielding to the pressure upon them until the adhesion of the valve upon the plate A is overcome, and the valve started, the spring impels it to a quick motion, and it goes to its place.

The reciprocating or alternating rotary motions of C make it necessary, in connecting the journal f to the ordinary meter-movements and indexes, to use a ratchet-wheel, D, (or equivalent,) to secure a complete rotary motion. The ratchet-wheel may be operated by means of an elastic catch, as seen in fig. 4, E, or by an ordinary pawl, as seen in fig. 6, and moved by the eccentric, h.

Fig. 5 shows how the levers a a may be entirely dispensed with, by simply placing arms upon C itself.

This meter may be regulated to suit any given index, simply by shortening or lengthening, as the case may require, the sweep of the forcing-plate C, by the set-screws *g g*, or by other mechanical modes.

The valve, also, need not be confined to this mode of construction. A direct movement will work just as well as a rotary one.

I have thus given a clear description of the principles embraced in the construction of the meter, and such merely mechanical changes as the manufacturer may prefer are not excluded.

I also regard this plan of a meter as entirely applicable for measuring gas.

Having thus fully described my invention, what I claim therein as new, and desire to secure by Letters Patent, is—

1. The water-ways *o o o o* through the plate A, in the manner and for the purpose herein set forth.
2. The forcing-plate C, upon its journals *f*, operated by the water, substantially in the manner and for the purposes herein set forth.
3. The springs *d d*, used in operating the valve B, substantially in the manner and for the purpose herein set forth.
4. The levers *a a* and regulating-screws *g g*, substantially in the manner and for the purpose herein set forth.
5. The dividing-plate *e*, substantially in the manner and for the purpose herein set forth.

GEO. R. MOORE.
